UNITED STATES PATENT OFFICE.

PETAR EIFRIED, OF PASSAIC, NEW JERSEY.

ATTACHMENT FOR FIRE-ALARM BOXES.

1,311,881.

Specification of Letters Patent.

Patented Aug. 5, 1919.

Application filed November 16, 1918. Serial No. 262,808.

To all whom it may concern:

Be it known that I, PETAR EIFRIED, a subject of the King of Hungary, residing at Passaic, county of Passaic, and State of New Jersey, have invented certain new and useful Improvements in Attachments for Fire-Alarm Boxes, of which the following is a specification.

This invention relates to improvements in fire alarm boxes and has as its special object the provision of means whereby a person attempting to give an alarm is restrained from leaving the box, thereby deterring unwarranted alarms.

15 A further object is to provide such devices with means for ready attachment or detachment from a fire alarm signal box, or like device.

Another object is to provide means, combined with the attachment, which will show the attempted intrusion of a person's hand to the operative device of the signal box, and

20 Finally to provide means combined with the device whereby a person may be liberated by those authorized.

These and other like objects are attained by the novel construction and combination of parts hereinafter described and shown in the accompanying drawings, forming a material part of this disclosure, and in which—

25 Figure 1 is a partial side elevational and sectional view, showing an apparatus made in accordance with the invention, the section being taken substantially on line 1—1 of Fig. 4.

Figure 2 is a fragmentary perspective view indicating the application of the invention.

30 Fig. 3 is a fragmentary transverse sectional view taken on line 3—3 of Fig. 1.

Fig. 4 is a transverse sectional view taken on line 4—4 of Fig. 1, the parts being shown in a closed position, and,

35 Fig. 5 is an end view of the apparatus with the cover removed, the parts being shown in an open position.

In Fig. 2 of the drawings a conventional type of post is indicated by the numeral 10, the same having a base, the post being hollow to accommodate the wires usually employed 40 connecting with the alarm box 12, rigidly engaged with the post by bands 14, and having the door 15 secured in the usual manner.

Attached to this door or cover 15, and at a slightly downward tilting angle as indi-

cated by the two center lines in Fig. 1, of which the upper one indicates a horizontal direction and the lower the downward tilt of casing 18, is a hollow cylinder 18 by means of a flanged base 19, its opposite outer end 20 being enlarged and provided with an annular cap or cover 21, secured by a hinge 22 upon one side, while upon the opposite side, attached by the hinge 23 is a clip 24 engageable over the edge 25 of a recess formed in the enlarged portion 20 of the cylinder. 55

The cover constitutes in effect a frame having a circular opening 26 and secured adjacent to the flanged portion 21, by a hinge 27, is a flat ring 28, having an opening 29, in register with the opening 26, the ring 70 being clamped closely against the inner side of the cover plate by an extending flat button 30, pivoted by its stem 31, to the cover plate 21, the ring 28, containing a slot 32 through which the button 30 may pass when 75 clamping the ring and cover element 21 firmly together.

In order to easily operate the ring a finger pull 33, is secured to the inside of the ring so that when the button is turned to register 80 with the slot 32, the ring may be swung upon its hinge permitting the insertion of a diaphragm 60 of paper or other preferred material, which closes the opening entrance to the outer end of the cylinder, the dia- 85 phragm however, being so made that it may be readily broken upon the insertion of a person's hand.

A cutaway portion or recess 35 is formed in the cylindrical walls of the enlargement 90 20, and fitted to be received, therein, is a curved filler plate 36, while secured over the filler plate 36, is a cover plate 38 having extending marginal edges adapted to make intimate contact and overlay the marginal 95 edges of the cut out portion 35 preventing entrance of snow or water to the interior of the casing, the cover plate being engaged at one end by the hinge 37, to the exterior of the wall 20. 100

Pivoted to the end of the cover plate, opposite the hinge 37, is another hinge element 39, carrying a pin 40 by which is engaged a hasp 41, having an opening receptive of the staple 42 secured in the wall 20, and in order 105 to secure the cover plate to the wall a padlock 43 may be engaged in the staple 42 maintaining the covers in a close relation,

- Fixed rigidly within the walls, of the casing 20, at spaced intervals, are two pairs of lugs 45 and 45', and secured by pins 47, are bracket elements 48 and 48', formed with segments 50 and 51, having beveled inner faces, the segment 51 having attached to it one end, of a coiled tension spring 52, the other end being engaged in an eye extending inward from the cylinder wall 20.
- 10 Similarly pairs of lugs 46 and 46' extend inwardly from the filler plate 36, and secured by pins 47 are bracket elements 53 and 53' extending from other segments 54 and 55 coöperating to form a circle when the filler and cover plate are clamped to the body of the cylinder, the effect of the spring 52 being to hold the segments substantially radial with respect to the structure.
- Secured upon the outer side of each of the segments at one end thereof, are clips 56, having extending portions adapted to engage with the adjacent ends of the next succeeding segments, forming an interlocking arrangement whereby all of the several 25 segments are held in substantially circular formation, which is materially assisted due to the operation of a single clip 58 secured to the back of the segment 51.
- 30 In operation, the casing having been secured in the front of an alarm box in such manner as to inclose the handle or key by which it is operated, the diaphragm 60, which prevents entrance of water, rain or the like from the end, and which must be punctured or broken to obtain access to the interior, is then clamped between the cover 21 and plate 28.
- Upon inserting the hand it will come in contact with the beveled segments, opposing 40 the spring 52, the segments yielding so as to permit the insertion of the hand through the central opening formed therebetween, and permitting manipulation of the key or operating handle, designated generally by 45 the numeral 61, which extends inwardly from the base end of the cylinder 18. When, however, an attempt is made to withdraw the hand, the segments close upon the wrist, preventing its retraction and holding the 50 person engaged with the device until a proper officer arrives, opening the lock 43, turning outward the cover plates 36 and 38 and thereby releasing the hand of the person giving the alarm.
- 55 From the foregoing it will be seen that an effective device for preventing the escape of a person giving the alarm has been disclosed, thereby avoiding the frequent occurrence of false alarms by evil intentioned or 60 unauthorized persons.

Having thus described my invention what

I claim as new, and desire to secure by Letters Patent, is—

1. In an alarm box attachment, the combination with a hollow cylindrical casing, and means for connecting said casing with an alarm box, said casing having an opening formed transversely in its wall, covers for the mentioned opening, means for securing said covers in position, a plurality of yieldingly mounted segmental elements secured within said casing, other similar segments pivoted to the inner side of said covers, means for holding said segmental elements in an operative position, and means for releasing the said segments mounted upon said cover plate. 70

2. In an attachment for alarm boxes, the combination with a cylindrical casing and means for attaching said casing to the operative face of a box, of a cover hingedly engaged at the open outer end of said casing, a diaphragm removably engaged with said cover through which an entry may be made, a lateral recess formed in said casing adjacent to said cover, a plate adapted to cover said recess, means for securing said plate in position, lugs secured interiorly of said casing, other lugs engaged with the inner surface of said cover, a plurality of yieldingly mounted segmental elements attached to each of said lugs, said elements when in operative position comprising substantially a circle having central opening, and means for holding said segmental elements in a substantially radial operative position, said segments being adapted to retain a band entered therebetween. 90

3. In an attachment for alarm boxes, the combination with a cylindrical casing having an enlarged head, and means for attaching the base of said casing to an alarm box, of a lateral recess formed in said enlarged head, a filler plate hingedly to enter within said recess, a cover plate disposed over said filler plate, lugs extending inward from said filler plate, other similar lugs extending inward from the interior of said casing enlargement, a plurality of segmental elements yieldingly engaged upon pivots in said lugs, said elements forming substantially a complete circle and having an annular opening at their inner extremities, means for locking said cover plate in an adjusted position, means for holding said segmental elements in a radial extended operative position, and means for securing a diaphragm upon said cover, said diaphragm being disruptable in nature. 105

In testimony whereof I have affixed my 120 signature.

PETAR EIFRIED.
